COMBINATION WALL SHELF AND PLANTER
UNIT

Alfred B. Stotter, Cleveland Heights, and Anthony J. Vaiksnoras, Cleveland, Ohio, assignors to Transparent Specialties Corporation, Cleveland, Ohio, a corporation of Ohio

Application July 11, 1951, Serial No. 15,822

Term of patent 14 years

(Cl. D35—3)

To all whom it may concern:

Be it known that we, Alfred B. Stotter and Anthony J. Vaiksnoras, respectively, citizens of the United States of America, residing respectively at Cleveland Heights, county of Cuyahoga, and State of Ohio, and Cleveland, county of Cuyahoga, and State of Ohio, have invented a new, original, and ornamental Design for a Combination Wall Shelf and Planter Unit, of which the following is a specification, reference being had to the accompanying drawing, forming a part hereof:

Fig. 1 is a top plan view of a combination wall shelf and planter unit embodying our new design;

Fig. 2 is a front elevational view thereof;

Fig. 3 is a rear elevational view thereof;

Fig. 4 is an end or side elevational view thereof, as viewed from the right side of Fig. 2, and

Fig. 5 is a cross-sectional view, taken on the line 5—5 of Fig. 2.

We claim:

The ornamental design for a combination wall shelf and planter unit, substantially as shown.

ALFRED B. STOTTER.

ANTHONY J. VAIKSNORAS.
